Patented May 11, 1971

220,701

CHRISTIAN MEDALLION OR SIMILAR ARTICLE

Joseph A. Honzik, 2120 34th St.,
Two Rivers, Wis. 54241

Filed Oct. 28, 1969, Ser. No. 19,756

Term of patent 14 years

Int. Cl. D11—02

U.S. Cl. D29—23

FIG. 1

FIG. 2

FIG. 3

FIG. 1 is a front elevational view of a Christian medallion showing my new design;

FIG. 2 is a top plan view thereof; and

FIG. 3 is an edge view taken from the right of FIG. 1.
I claim:

The ornamental design for a Christian medallion or similar article, substantially as shown.
